UNITED STATES PATENT OFFICE.

GEORGE R. FARRELL, OF WYANDOTTE, MICHIGAN.

LANTERN.

1,164,797.

Specification of Letters Patent. Patented Dec. 21, 1915.

Application filed March 20, 1915. Serial No. 15,698.

To all whom it may concern:

Be it known that I, GEORGE R. FARRELL, citizen of the United States, residing at Wyandotte, county of Wayne, State of Michigan, have invented a certain new and useful Improvement in Lanterns, and declare the following to be a full, clear, and exact description of the same, such as will enable others skilled in the art to which it pertains to make and use the same, reference being had to the accompanying drawings, which form a part of this specification.

My invention relates to an improvement in the general construction of lanterns adapted to manufacture and burn acetylene gas; the same being shown in the accompanying drawings and more particularly set forth in the following specification and claim.

20 One of the objects of this invention is to simplify the general construction, and to reduce the cost of manufacture, by the elimination of a number of parts usually required in a lantern of this character.

25 One salient feature of the invention is the elimination of the usual air vent opening into the water chamber, and the substitution of a passage between the gas chamber and the top of the water chamber that the water 30 in the latter may be under pressure that it may flow freely into the carbid chamber upon opening the valve controlling its discharge. The usual vent is objectionable on account of the water discharging or spilling 35 through the opening when the lantern is swung or tilted, as required in railroad signaling.

Another feature of the invention consists in providing means whereby any excessive 40 pressure of gas in the gas chamber which may operate to distinguish the light may be relieved.

Another feature of the invention consists in so constructing the base of the lantern 45 that it may be employed as one of the telescoping parts of the carbid storage chamber thus eliminating one part, it being customary to construct the carbid chambers of two independent telescoping members housed 50 in the base of the lantern.

Another feature of the invention consists

in joining the body of the lantern with the upper structure at a point directly above the carbid chamber by a screw threaded connection between the base and the water chamber, thereby insuring a tight joint and providing a gas storage chamber intermediate of the water and carbid chambers, which are spaced apart for that purpose, thus insuring a continuous and steady flow 60 of gas to the burner.

Another feature of the invention consists in attaching a spring to the inverted telescoping cup of the carbid chamber which serves to force the cup directly upon the carbid to provide against its dislodgment, and upon disengaging the base from the water chamber above,—the spring may be used as a bail for the withdrawal of the inverted telescoping cup to remove or renew 70 the carbid in the chamber.

A further object is the means provided for locking the lantern supporting bail to its frame that it may be used for railroad signal purposes, the construction however 75 providing for its ready release for use as an ordinary swinging lantern.

Other advantages and improvements will hereafter appear.

In the drawings accompanying this specification:—Figure 1, is an elevation partly in section of a lantern embodying my invention. Fig. 1^a, is a detail view of a fragmentary portion of the lantern bail and its supporting bracket.

Referring now to the letters of reference placed upon the drawings:—A, denotes the base of the lantern forming also one portion of the carbid chamber B.

C, is an inverted cup-shaped element telescoping in the carbid chamber B, and adapted to bear upon the carbid contained therein that it may not be displaced with the swinging of the lantern. The upper edge of the base portion A, is threaded to engage the screw threaded flange d, of the water chamber D.

D', is a tube extending downwardly from the water chamber into a slotted tube E, sleeved in the depending flange c, of the inverted cup-shaped carbid member.

F, is a tube opening into the water cham-

ber and extending into the tube D' its lower end being formed with a valve seat f' , under control of the needle valve F'.

F², is a swinging arm secured to the stem of the valve F', by which the latter may be adjusted to discharge water from the water chamber into the depending tube D'. The water passes thence out through the slots of the telescoping tube E into the carbide chamber generating a gas upon contact with the carbide, which passes to the gas chamber G through the ports c', in the wall of the inverted cup.

H, is a tube opening into the gas chamber G, and extending up through the water chamber, its top being fitted with a lavatip or other gas burner H'.

I, is a tube opening into the depending tube D', and passing out through the water chamber with a return bend above opening into an auxiliary chamber J. The auxiliary chamber is divided by a perforated baffle-plate J', its lower wall entering the space above the water chamber which is provided with an aperture for the delivery of gas into the water chamber, the aperture in the lower wall J² being in staggered relation to the aperture in the baffle-plate above, that the water in the chamber may not easily be discharged through the apertures through swinging of the lantern.

K, is an imperforate filler cap by removing which the water chamber may be filled.

L, denotes a vent tube opening into the gas chamber and projecting down through the base of the lantern its end being closed by a screw threaded cap L' having a transverse opening L², which may be adjusted to provide a vent for the gas chamber to relieve any excessive pressure.

L³, is a stop to limit the adjustment of the cap and to insure against its loss or displacement.

M, denotes the usual globe supported upon the ledge f, formed in the wall of the water chamber.

N, is a cowl perforated for ventilation supported by the globe guard frame N'.

O, is a bail pivoted to the ears n, n, of the guard frame, one arm of the bail being flattened as indicated at O', and slotted as at O², to form tines O³, adapted to project on either side of the ear n, of the frame when attached to the inner face of the latter. A lantern having a rigid bail may thus be provided for signal purposes, but should it be desired to convert the lantern into one having a swinging bail it is only necessary to disengage the pivot bolt P, and connect the bail O², to the outside of the ear n, replacing the pivot bolt,—it being obvious that the bail is then free to swing with respect to the guard frame. The cowl is fitted on the inside with a spring Q, adapted to bear against the upper wall of the cowl at one end and at

the other end against a cross member Q' resting upon the top of the globe M, whereby the latter is held against displacement.

Having indicated the several parts by reference letters the construction and operation of my device will be readily understood.

The inverted cup in the base of the lantern is first removed and filled with carbide, the cup is then placed in position and the base is screwed to the downwardly projecting flange of the water chamber. The cap K, is then removed from the water chamber and the latter charged with water to a suitable height. The globe is then replaced and the valve F adjusted to permit the passage of water from the water chamber to the valve tube leading into the depending tube D', from whence it passes through the slotted telescoping member of the carbide chamber and out into the latter. Should the water fail to freely flow from the water chamber when the lantern is initially lighted, the cap L, of the vent tube may be adjusted to admit air which will serve to relieve the "air bound" condition of the water chamber. Immediately upon the formation of gas the vent tube may be closed the gas passing up through the burner tube H for ignition,—

a portion of the gas flowing through the pipe I, by way of the auxiliary chamber J, into the water chamber providing pressure to assist in the discharge of the water therefrom by way of the valve controlled discharge port f. If the formation of gas is too rapid or the pressure excessive causing the burner to "blow" the vent pipe L, may be opened by the adjustment of the cap to temporarily relieve the excessive pressure in the gas chamber, it may then be closed. It will also be obvious that a proper adjustment of the valve F' controlling the delivery of water to the carbide chamber will serve to govern the volume and formation of gas delivered to the gas chamber.

Having thus described my invention what I claim is:—

In a lantern of the character described, a hollow base and an inverted cup fitted therein to form a carbide chamber, the upper end of the base being screw threaded, a water chamber having a screw threaded extension connecting with the screw threaded upper outer end of the base a gas chamber thus formed between the water chamber and the inverted cup which has communication with the carbide chamber through apertures formed in the inverted cup shaped member, a spring between the inverted cup shaped member and the water chamber, a tube depending from the water chamber and extending through the inverted cup shaped member, a slotted tube, depending from the inverted cup shaped member and embracing the first-named tube, a valved passage between the

water chamber and the first named tube, a gas tube extending through the water chamber and partly through the first-named tube to convey gas from the gas chamber through the water chamber, a burner on the outer end of the gas tube, and an L-shaped pipe leading from the gas chamber to the base of the lantern exteriorly of the carbid chamber.

In testimony whereof, I sign this specification in the presence of two witnesses.

GEORGE R. FARRELL.
